CONTAINER WITH SPRING-LATCH CLOSURE

Robert C. Shipley, Kalamazoo, Mich.

Application June 7, 1946; Serial No. 675,034

13 Claims. (Cl. 206—1.5)

1

This invention relates to an improved container closure and is more specifically concerned with such means operable by a single, simple manual movement and having no externally visible parts when the container is closed.

While innumerable means have from time to time been provided for holding container closures in closed position relatively few of them are both effective and also entirely concealed from external view when the container is closed. Nevertheless, in providing for a high grade product an attractive container, such as a container made from highly polished mahogany, it is desirable that the container be not disfigured when it is in closed condition by externally visible hinges, plates, latches or other conventional closure holding means.

It is further desirable in providing such a container closure that it be operable by a simple manual movement so that the container may be opened or closed with a minimum of effort. However, this ease of operation should not be accomplished by any sacrifice of firm holding when the container is in a closed condition.

Further, when the container is used in the distribution of a high grade article of commerce, such as a finely made shaving razor, where it will be manipulated with considerable frequency over a long period of time, it is especially desirable that the closure mechanism not only act smoothly and positively but that it have a minimum of moving parts and a maximum of sturdiness and durability.

Therefore, a principal object of this invention is to provide means for maintaining a container in a closed condition without recourse to an outside latch or other conventional means of closure member holding.

Another object of the invention is to provide a means for securing a cover for a container body firmly in place by a rapid single movement in such a manner that the cover will remain in that position without slippage.

Another object of the invention is to provide a means for securing a container body and a co-operating cover firmly together in closed relationship which will conceal from external view all elements of the cover holding means when said parts are in such closed relationship.

Another object of the invention is to provide means as aforesaid which will operate cleanly and firmly and which will have a high degree of durability and resistance to wear and rough usage.

A further object of the invention is to provide

2

a container body and cover, and locking means integral therewith adapted automatically to engage the cover when placed on the container body, and to lock it in closed position.

A further object of the invention is to provide container and closure means as aforesaid which are of such simple construction that the fabrication thereof can be effected rapidly and inexpensively.

Other objects and purposes of the invention will be apparent to those acquainted with articles of this type upon inspection of the following specification with reference to the accompanying drawing.

Figure 1 is a side elevation of a container in partially open position having first, or bottom, and second, or top, cooperating members in face-to-face contact and provided with the closure holding means of the invention.

Figure 2 is an end elevation of the container of Figure 1.

Figure 3 is a sectional view taken on the line III—III of Figure 1.

Figure 4 is a plan view of the under side of the top, or cover, member of the container.

Figure 5 is a plan view of the upper side of the bottom member of the container.

Figure 6 is a sectional view taken on the line VI—VI of Figure 4.

Figure 7 is a sectional view taken on the line VII—VII of Figure 5, said Figures 6 and 7 being juxtaposed to show the same relationship of parts as appears in Figure 3.

Figure 8 is a sectional view taken on the line VIII—VIII of Figure 5.

Figure 9 is a part sectional view taken on the line IX—IX of Figure 5.

Figure 10 is a part sectional view similar to that of Figure 7 showing a modified form of my invention.

Figure 11 is a part sectional view similar to that of Figure 9 showing further details of said modification.

Figure 12 is a portion of Figure 5 drawn on an enlarged scale and showing superimposed thereon in dotted outline the pin guiding slot in one relative position it occupies when the container is closed.

Figure 13 is a portion of Figure 5 drawn on an enlarged scale and showing superimposed thereon in dotted outline the pin guiding slot in the relative position it occupies when the container closure is retracted and ready for removal from the container.

The invention comprises essentially a container

having a container body member and cover, or closure, member herein referred to for convenience as a first, or bottom cooperating member and a second, or top, cooperating member, respectively, which may be constructed of wood, metal, plastic or other suitable material and which may in general outline be of any suitable shape. The parts are held together by cooperating means when in closed position, and they have associated therewith closure holding means which are entirely concealed from view when the cover is placed on the container body and moved into closed position. The container is particularly characterized by the fact that at least a certain portion of the facing surfaces of the cooperating members are at least partially planar and that these planar surfaces, herein referred to as faces, are in face-to-face contact during the time the cooperating members are in closed relationship and in sliding face-to-face contact during the movement of the cover to open or close the container, as will be hereinafter described. For convenience, and without intending any limitation, movement of the cover with respect to the container body to close the container is referred to as movement in the "forward" direction, and reverse movement is referred to as movement in the "rearward" direction. Likewise, the end of the box, or parts thereof, appearing at the left in Figure 1 will sometimes hereinafter be termed "forwardly" or "forward" end and the other end of the box, or parts thereof, will sometimes hereinafter be termed "rearwardly" or "rearward" end.

Although the invention will be described with certain elements of the closure means associated with the first of the cooperating members and certain other elements of the closure means associated with the second of the cooperating members, it will be apparent as the description proceeds that the location of these elements may be reversed, if desired, and, furthermore, that the designation of either particular one of the cooperating members as the container body and the other one as the container cover is purely arbitrary and for the sake of convenience only. Also, by way of simplifying the description, the relative movement of the cooperating members when the container is closed and opened is referred to merely as the movement of the second cooperating member, or cover, into closed or open position, respectively. It will be further apparent that the shape of the interior of the container is immaterial and the invention is not limited thereby. In the drawing there is shown for illustrative purposes a mahogany container adapted to house a safety razor during shipment and also to serve as a desirable storage container therefor between periods of use, this being but one of the many uses for which the container and closure means of the invention are adapted.

Referring now to Figure 1 a first cooperating member 21 and a second cooperating member 22 having planar contacting faces 27 and 28, respectively, are disposed so as to slide in face-to-face contact upon one another. Each of the cooperating members is shown substantially rectangular in cross-section, as in Figure 3, although it is apparent that they may be of any other convenient shape, provided they are adapted to slide in face-to-face contact. Each of the members 21 and 22 is provided with an end member, ends 23 and 24 respectively, secured to, as by gluing, and projecting beyond the end surface of each respective member so as to abut the end of

the other member when the container is in closed position. The end members thus lend a neat appearance to the ends of the container, as illustrated in Figure 2, and also serve as stops to limit the forward motion of the cover member 22 when the container is closed.

5 A groove 25 is provided in the projecting portion of the end member 23 of the first cooperating member 21 and a pair of cooperating lugs 26 10 are provided on the end of the second cooperating member 22 so as to engage the groove 25 when the container is in closed position. A similar groove and cooperating lugs, 30 and 32, are provided at the opposite end of the container. A tongue 29 extending from one planar contacting face is received into a guide-groove 31 in the opposite planar contacting face, by which relative longitudinal motion of the container parts is permitted but relative transverse motion prevented.

15 Referring now to Figures 5 and 8, the closure holding means comprises a pin-travel slot 33 located in a face 27 of the first cooperating member 21 in such a manner as to guide the travel 20 of a pin 38, which protrudes therethrough and extends for some distance beyond the said face of the cooperating member. Below the pin-travel slot is a cavity or slider well 34 extending longitudinally through a portion of the member 21 25 and communicating with the bottom of the pin-travel slot. A resilient means 35, such as a spring, is positioned in the slider well and serves to continuously urge a slider 36, such as a wooden plug or piston fitted loosely into the cavity, forwardly 30 in the slider well. The pin 38 is secured in fixed position to the slider and thus travels in the pin-travel slot as the slider travels in the slider well. The formation of the slider well and the assembling 35 of the spring, slider and pin are effected conveniently before the end member 23 is secured to the first cooperating member 21.

35 A pin-retaining means is provided at the rearward end of the pin-travel slot and may consist conveniently of a notch 39 cut in the side of the pin-travel slot so as to provide a shoulder 40 40 constituting a square or even very slightly concave abutment for the retaining of said pin. When the pin 38 is first moved rearwardly to the limit of its travel and then its upper end moved laterally with respect to its line of travel in such manner that the slider rotates slightly in the slider well, the pin engages the shoulder 40 and is effectively retained and prevented from traveling in a forward direction.

45 A pin-engaging slot 41 (Figure 4) is provided in the face of the second cooperating member, or cover, of the container and is so situated and aligned therein that when the two cooperating members 21 and 22 are in face-to-face contact, the portion of the pin 38 extending above the face of the first cooperating member 21 is received by the pin-engaging slot. The pin-engaging slot 41 and the pin-travel slot 33 are further aligned so that when the cooperating members 21 and 22 are in face-to-face contact, they lie at an acute angle with respect to each other, in the illustrated embodiment approximately 45°.

50 The manner of cooperating of the pin 38, the pin-travel slot 33 and the pin-engaging slot 41 are shown in Figures 12 and 13. When the cooperating members 21 and 22 are in closed position, the pin 38, which is urged forward by the spring 35, presses against the forward edge of the pin-engaging slot 41 as shown in Figure 12, 55 and serves to maintain the container in closed

position whereby the cooperating members 21 and 22 are held firmly together by the cooperating grooves and lugs 25 and 26, 30 and 32 mentioned previously. When the second cooperating member 22 is slid rearwardly to disengage the cooperating grooves and lugs, the pin 38 is simultaneously moved rearwardly against the urging of the spring 35 and, due to the angle between the pin-travel slot 33 and the pin-engaging slot 41, the sloping side of the latter urges the pin sideways against the wall of the pin-travel slot. At the end of its travel, the pin is thrown by such urging into the notch 39 and thus into retaining engagement with the shoulder 40, as shown in Figure 13.

When the pin has reached the rearward limit of its travel and has engaged the pin-retaining means, the second cooperating member may be lifted away from the first cooperating member, the pin remaining in position to engage the said second cooperating member, or cover, when it is replaced. In replacing the second cooperating member and closing the container, it is only necessary to place the two cooperating members in face-to-face contact in such position that the tongue 29 is received into the groove 31 and the pin 38 projects into the pin-engaging slot 41. To enable this latter to be done easily and accurately, guide marks 42 of Figure 1 may be positioned on the sides of the cooperating members, it thus being only necessary to see that these guide marks are aligned when the cooperating members are placed in face-to-face contact. A simple forward movement of the second cooperating member 22, by the action of lateral urging on said pin of the rearward wall of the angularly placed pin-engaging slot 41, then suffices to disengage the pin from the pin-retaining means and the cover is promptly urged into closed position by the pin pressing in a forward direction on the forward edge of the pin-engaging slot.

Although the pin 38 is normally prevented by the wall of the pin-engaging slot from traveling forward far enough to contact the forward end of the pin-travel slot, the end of the slot serves effectively to limit the forward travel of the pin in the slot; if the pin does accidentally become disengaged from the pin-retaining means while the cooperating members are separated, thus preventing dislocation of the mechanism.

The pin 38 is preferably positioned with its longitudinal axis in a plane substantially perpendicular to the longitudinal dimension of the face 27 of the first cooperating member 21 as shown in Figures 7 and 8. It need not, however, be perpendicular to a line in the said face transverse to the line of travel of the pin-travel slot so that the pin assumes a definite outwardly inclined position with respect to such line, as shown in Figures 10 and 11, since by so doing a wider shoulder may be utilized as the pin-retaining means without rotating the slider 36 so far inwardly that said pin extends into the interior of the container.

Alternative to the structure here specifically described and illustrated, the guide-groove 29 can be placed in the surface 27 and preferably, but not necessarily, is aligned on the center line of the pin-travel slot 33. A tongue corresponding to the tongue 31 will then be caused to extend from the surface 28 to cooperate with the said guide-groove. By this variation all work is done on the same side of the box and a few fabricating steps thus avoided.

Other variations and modifications from the form herein specifically shown and described for illustrative purposes will be apparent to those acquainted with articles of this type, so that the hereinafter appended claims should be restricted in their scope only as expressly required by their specific terms.

I claim:

1. In a container comprising first and second cooperating members held together in face-to-face closed, or forward, position by a plurality of engaging means and movable out of closed position, or rearwardly, by sliding movement of the one cooperating member along the face of the other cooperating member, means releasably holding said members in closed position, comprising: means providing a pin-travel slot located in the face of the first cooperating member and aligned substantially parallel to the direction relative thereto of said sliding movement of said second cooperating member; means providing an elongated slider well within the body of said first cooperating member communicating with the bottom of said pin-travel slot and parallel longitudinally thereto; a slider located in the slider well adapted to travel longitudinally therein and free to rotate at least through a small angle around the axis of its line of travel; a spring located in the slider well rearwardly of the slider and adapted to urge the slider forward in container closing direction throughout the range of its travel; a pin having its longitudinal axis in a plane perpendicular to the face of the first cooperating member and secured in fixed position to the slider, said pin being adapted to travel in the pin-travel slot and protruding therefrom beyond the face of the first cooperating member; a lateral recess and pin retaining shoulder in the rearward portion of a sidewall of the pin-travel slot adapted to engage and retain the pin at the rearward limit of its travel upon rotation of the slider in the slider well; means providing a pin-engaging slot located and aligned in the face of said second cooperating member for crossing said pin-travel slot at an acute angle and extending when the cooperating members are in closed position and during said sliding movement, away from said pin travel slot on the same side thereof as the extension of said lateral recess and being inclined toward the end of said pin-travel slot approached by said pin as said container closes, whereby engagement of said pin with said pin-retaining means is effected by the second cooperating member sliding rearwardly, and disengagement of the said pin from said pin-retaining means is effected by the second cooperating member sliding forwardly; and cooperating means in contacting faces of said cooperating members parallel to the line of said sliding movement preventing lateral movement of the cooperating members when they are in face-to-face contact.
2. In a container comprising first and second cooperating members held together in face-to-face closed, or forward, position by a plurality of engaging means and movable out of closed position, or rearwardly, by sliding movement of the second cooperating member along the face of the first cooperating member, closure means cooperating therewith comprising: means providing a pin-travel slot located in the face of said first cooperating member; means providing an elongated slider well within the body of said first cooperating member communicating with said pin-travel slot and parallel thereto; resilient means located in said well; an axially rotatable slider in said slider well adapted to travel therein forwardly in

response to, and rearwardly against, said resilient means; a pin secured in fixed position to said slider and adapted to travel in said pin-travel slot and protruding beyond the face of the first cooperating member; pin-retaining means including a laterally extending recess in said face of said cooperating member, communicating with said pin-travel slot and adapted to engage and retain said pin at the rearward limit of its travel upon limited rotational movement of said slider; means providing a pin-engaging slot located and aligned in the face of said second cooperating member and crossing said pin-travel slot at an acute angle and extending, when the cooperating members are in closed position and during said sliding movement, away from said pin-travel slot on the same side thereof as the extension of said lateral recess and being inclined toward the end of said pin-travel slot approached by said pin as said container closes whereby engagement of said pin with said pin-retaining means is effected by the second cooperating member sliding rearwardly and disengagement of the said pin from said pin-retaining means is effected by the second cooperating member sliding forwardly; and cooperating means in contacting faces of said cooperating members preventing relative lateral movement thereof when in face-to-face contact.

3. In a container comprising first and second cooperating members held together in face-to-face closed, or forward position by a plurality of engaging means and movable out of closed position, or rearwardly, by sliding movement of the one cooperating member along the face of the other cooperating member, closure holding means cooperating therewith comprising: means providing a pin-travel slot located in the face of said first cooperating member; a pin adapted to travel in said pin-travel slot forwardly in response to and rearwardly against resilient means and protruding beyond the face of the first cooperating member; pin-retaining means at one side of said pin-travel slot and adapted to engage and retain said pin at the rearward limit of its travel; means providing a pin-engaging slot located and aligned in the face of said second cooperating member for crossing said pin-travel slot at an acute angle and extending, when the cooperating members are in face to face, or sliding, positions, toward said one side of said pin-travel slot and inclined toward the forward end of said pin-travel slot, said pin engaging slot being adapted to engage said pin throughout the length of its travel whereby engagement of said pin with said pin-retaining means is effected by the second cooperating member sliding rearwardly and disengagement of the said pin from said pin retaining means is effected by the second cooperating member sliding forwardly; and means in contacting faces of said cooperating members preventing relative lateral movement thereof when in face-to-face contact.

4. In a container closure movable into and out from container closing position by relative sliding movement and wherein said closure and container are provided with interlocking closure retaining means operable when said closure is in closed, or forward, relationship with said container, in combination therewith the improvement comprising: resiliently slidable means urging said closure toward said forward or interlocking position comprising a pin mounted in one of said members and extended toward the other of said members when same are in operative position for movement of said pin parallel to the direction of said relative sliding movement and re-

silient means urging said pin in closure closing, or forward, direction; means permitting lateral movement of at least a portion of said pin at the rearward end of its said travel and means engaging said pin when in such laterally moved, or engaged, position preventing its movement out of said retracted position; means associated with the other of said members urging said pin backwardly and laterally into said engaged position as said closure member is slidably moved rearwardly out of interlocking position and urging said pin in a lateral direction out of said engaged position as said closure member is moved forwardly toward interlocking position.

5. For a container member having a sliding closure member, said closure member having means interengaging with said container member holding said members against separation when in fully closed, or forward, position, means in combination therewith for detachably holding said closure and said container in fully closed position comprising: means providing a slot in the face of one of said members located adjacent the other of said members when in operative position which slot is aligned at an acute angle to the direction of relative movement between said members as same are moved into and out from interengaging, or forward, position said angle opening toward the direction of movement of said one member as the container closes; means providing a slot in the surface of the other of said members which surface faces said one of said members when they are in operative position and which slot is aligned parallel with the direction of said relative movement and having a recess at that end thereof representing the retracted or rearward position of the hereinafter mentioned pin and extending sidewardly in the same direction as the sideward extension of the slot in said first named member; a pin slidably positioned in said last-named slot and extending beyond said surface; means holding said pin for guided movement within said last-named slot and recess, and resiliently urging same toward the position occupied by it when said members are in closed, or forward, position; said parts being arranged whereby said pin may be received into said angularly positioned slot when said members are in cooperative position.

6. In a container closure movable into and out from container closing position by relative sliding movement and wherein said closure and the container are provided with interlocking closure retaining means operable when said closure is in closed relationship with said container, the combination therewith of the improvement comprising: means resiliently urging the closure member and the container member toward interlocked position, said means including a longitudinally movable pin associated with one member and interengageable with said other member and at least partially laterally movable at that end of said longitudinal movement corresponding to the non-interlocked position of said members, and means receiving said pin when so laterally moved and holding said pin against movement in response to said resilient urging; means associated with the other of said members urging said pin backwardly and laterally as said parts are relatively moved for container opening, and urging said pin in reverse lateral direction out of said engaged position as said members are urged toward container closing position.

7. For a container member having a closure member slidable with respect thereto along a single line, said closure member having means in-

terengaging with said container member holding said latter member against separation therefrom when said members are in fully closed position, means in combination therewith for detachably holding said closure member and said container member in fully closed position, comprising: means resiliently urging said members towards interlocked position, said means including a pin associated with one member movable with respect thereto in a direction parallel to the direction of said line and interengageable with said other member, and at least partially laterally movable at that end of its movement corresponding to the non-interlocked position of said members, and means receiving said pin when so laterally moved and holding same against movement in response to said resilient urging; means in the other member providing a slot arranged at an acute angle to the direction of said longitudinal movement receiving said pin when said members are in cooperative position and extending away from said line of pin-travel in the same direction as said lateral movement and being inclined toward the interlocked position end of said pin-travel and urging said pin backward and laterally as said parts are relatively moved for container opening and urging said pin in reverse lateral direction out of said engaged position as said members are urged toward container closing position; means holding said members against movement relative to each other except along the line of said sliding.

8. For a container member having a sliding closure member and means detachably holding said members in closed position with respect to each other but permitting sliding movement out therefrom, the combination comprising: means providing a first slot in that surface of one member which is normally facing the other member, which slot is aligned at an acute angle to the direction of relative movement between said members as same are moved into and out from said closed position said acute angle opening in the direction of resilient urging of the hereinafter mentioned pin; means providing a second slot in a surface of the other of said members which surface faces said one of said members when they are in normal operative position and which slot is aligned parallel with the direction of said relative movement and said second slot having a recess extending sidewardly in the said same direction as said first named slot is inclined to said second slot and at that end thereof occupied by the hereinafter mentioned pin when same is in its retracted position; a pin slidably positioned in said second slot and extending beyond said surface adjacent thereto and receivable into said first slot when said members are in normal cooperative position; means holding said pin for guided movement within said second slot and resiliently urging same toward the position occupied by it when said members are in said closed position; means permitting sliding movement between said parts along a single line preventing relative movement transverse thereto.

9. A chambered member and a closure member relatively slidable along a single line toward and away from a selected position with respect to each other and means in combination therewith yieldably urging said members toward said selected position comprising: means providing an L-shaped slot in a portion of one of said members normally facing the other of said members; said slot having one leg thereof aligned parallel with said single line; a pin and means supporting same

within said slot for movement bodily in said one leg thereof and for sector-defining movement into the other leg of said slot; means urging said pin toward the end of said one leg of said slot remote from its connection with the other leg thereof; means providing a slot in said other member receiving said pin which slot is positioned at an acute angle to the said one leg of the L-shaped slot, and extends away from said one leg in the same direction as the extension of said other leg and inclined toward the end of said one leg remote from said other leg.

10. Means releasably holding in closed relationship to each other a container member and a closure member therefor mutually slidable along, and only along, a single straight line, comprising: a movable pin associated with one member having a portion extending away from said member and guide means supporting and guiding said pin for movement substantially transverse of its axis and parallel with the direction of said single straight line and laterally placed means located adjacent a portion of said guide means occupied by said pin when said members are in other than closed relationship and receiving said pin for holding same from movement in said guide means; diagonally aligned guide means inclined in the same lateral direction as said pin receiving means and in the direction of pin movement within said guide means away from said pin receiving means and associated with the other member receiving the extending portion of said pin; resilient means urging said pin in such direction as to move said members toward said closed relationship; means limiting movement of said other member in said straight line direction.

11. Means releasably holding in closed relationship to each other a container member and a closure member therefor mutually slidable with respect to each other along, and only along, a single straight line, comprising: a movable pin and means supporting same mounted on one member and having a portion of said pin extending away from said member, and pin guide means guiding said pin for movement substantially transverse of its axis and parallel with the direction of said straight line, and locking means extending laterally from the portion of said guide means adjacent a position occupied by said pin when the members are moved out of closed position, said locking means receiving said pin for holding same from movement in said pin guide means; diagonally aligned guide means having a portion thereof in registry with said pin guide means and extending from said portion transversely in the same lateral direction as said locking means and longitudinally in the direction of pin movement as said members are closing, and associated with the other member for receiving the extending portion of said pin; resilient means urging said pin in such direction as to move said members toward said closed relationship.

12. Means detachably holding a contacting face of a first member against an abutment and a contacting face of a second member, said means comprising: means guiding said members for relative movement in a line with respect to each other and preventing movement with respect to each other transverse to said line; an L-shaped pin guide slot in said contacting face of said first member having a first leg parallel to said line and a second leg transverse to said line; a pin within the said pin guide slot extending perpendicularly away from said face of said first mem-

bér and mounted in said slot for movement along the length of both legs of said L-shaped slot; means resiliently urging said pin in a direction parallel to said line and away from the second leg of said pin guide slot; an angular slot in the contacting face of said second member angularly positioned with respect to said line having one portion located in substantial register with the first portion of said L-shaped pin guide slot and extending laterally away therefrom in the same direction as the second leg of the said L-shaped slot and extending longitudinally away from the said second leg of said L-shaped slot; whereby, when said pin is received into the angular slot, upon retraction of said members away from a position effecting the contacting of said first member against the said abutment, one wall of said angular slot will urge said pin both longitudinally toward the end of that portion of said L-shaped slot parallel to said line at which is located the transverse portion thereof and laterally in the direction of the extension of said transverse portion of said L-shaped slot, and when said members are urged in a direction for effecting contacting by said first member of the abutment on said second member the other wall of said angular slot will first urge said pin out of the transverse portion of said L-shaped slot and then said pin under the urging of said resilient means will carry said second member toward the point of its contacting said abutment.

13. Means holding a contacting face of a first member against an abutment and a contacting face of a second member, said means comprising: means guiding said members for relative movement in a line with respect to each other and preventing movement with respect to each other

transverse to said line; a movable pin and means supporting same mounted on one member and having a portion of said pin extending away from said member, and pin guide means guiding said pin for movement substantially transverse of its axis and parallel with the direction of said line and locking means extending laterally from the portion of said guide means adjacent a position occupied by said pin when said first member is moved away from the abutment on said second member said locking means receiving said pin for holding same from movement in said pin guide means; diagonally aligned guide means having a portion thereof in registry with said pin guide means and extending from said portion transversely in the same lateral direction as said locking means and longitudinally in the direction of pin movement as said members are moved into abutting position and associated with the other member for receiving the extending portion of said pin; resilient means urging said pin in such direction as to move said members toward said abutting relationship.
